Henri Desguin, Koekelberg, and Nestor Sauvage, Berchem-Ste.-Agathe, Belgium, assignors to Fonderies Nestor Martin, Societe Anonyme, Berchem-Brussels, Belgium, a company of Belgium

Application April 27, 1950, Serial No. 9,524
In Belgium October 28, 1949

Term of patent 14 years

(Cl. D67—3)

To all whom it may concern:

Be it known that we, Henri Desguin and Nestor Sauvage, subjects of the King of the Belgians and residents of 24 Place Simonis, Koekelberg, Belgium, and 3 rue des Combattants, Berchem-Ste.-Agathe, Belgium, have invented a new, original, and ornamental Design for a Refrigerator, of which the following is a specification, reference being had to the accompanying drawing, forming a part thereof.

The figure is a perspective view of a refrigerator embodying our new design. The back is plain and the side, not shown, is like to the side shown.

We claim:

The ornamental design for a refrigerator, substantially as shown and described.

HENRI DESGUIN.
NESTOR SAUVAGE.
